(57) **CLAIM**

The ornamental design for an infant jumping device, as shown and described.

DESCRIPTION

FIG. 1 is a front perspective view of an infant jumping device according to the present invention;

FIG. 2 is rear view of the device of FIG. 1;

FIG. 3 is a front view of the device of FIG. 1;

FIG. 4 is a left side view of the device of FIG. 1;

FIG. 5 is a right side view of the device of FIG. 1;

FIG. 6 is a top view of the device of FIG. 1; and,

FIG. 7 is a bottom view of the device of FIG. 1.

The portions shown in phantom are for illustrative purposes only and form no part of the claimed design.
